UNITED STATES PATENT OFFICE.

FRANZ LÖSEL, OF BRUNN, CZECHOSLOVAKIA.

BACK-PRESSURE TURBINE AND METHOD OF UTILIZING HIGH-PRESSURE STEAM IN TURBINES.

Application filed April 7, 1923. Serial No. 630,661.

To all whom it may concern:

Be it known that I, FRANZ LÖSEL, a citizen of the Czechoslovakian Republic, and residing at 5 Glockengasse, Brunn, Czechoslovakia, have invented certain new and useful Improvements in Back-Pressure Turbines and Methods of Utilizing High-Pressure Steam in Turbines, of which the following is a specification.

10 My invention is an improved back pressure turbine and a novel method of utilizing high pressure steam for power purposes, which is availed of in my novel turbine. The object of my invention is to increase the efficiency of such turbines, the most marked increase being at the highest pressure stage thereof. By the practice of my invention, I am enabled to employ at very high efficiency much higher steam pressures and temperatures than have heretofore been employed for back pressure turbines, and at the same time I may employ back pressure turbines at pressures heretofore employed and obtain a greatly increased efficiency.

25 It is a recognized fact that the high pressure parts of back pressure turbines have heretofore been far less efficient than the high pressure cylinders of modern steam engines and that the methods and constructions employed have been such that the very high pressures which can be most economically produced in large steam generators and utilized in reciprocating engines could not be practically used in turbines.

30 In the Parson's or reaction type of turbine, in which approximately one-half of the pressure drops are in the rotor blades and therefore there is a substantial difference of pressure on opposite sides of each 35 rotor blade, a drum construction for the rotor was essential and relatively large clearances had to be provided. This type, because of the differences in pressure at the opposite sides of the rotor blades, required many stages and steam velocities throughout which were relatively low, usually 150 meters to 350 meters per second. In this type of turbine when used for the higher pressures the velocities were greatest at the 40 inlet end. This type of turbine was reasonably efficient for low pressures, but the clearance losses were so large at the higher pressures that it became usual to employ for back pressure turbines, turbines of the impulse type either with pressure stages, as in

the Rateau type, or with both velocity and pressure stages, as in the Curtis type.

This type of turbine could be, and has ordinarily been, constructed of the disc type because the pressure drops occur in the stationary diaphragms and there is only negligible difference of pressure on opposite sides of the rotor wheels. Therefore, a considerable clearance could be allowed and the leakage loss became negligible. This type of turbines, however, has always been designed for relatively great heat drops at each stage producing very high steam velocities and correspondingly high peripheral velocities of the rotor wheels. Moreover, the greatest heat drop occurred at the inlet to the turbine, and the highest steam velocity therefore occurred in the very first stage of the turbine. The great frictional and windage losses which result from these extremely high velocities caused a great loss of efficiency and set a limit to the pressures and temperatures which could be profitably utilized in impulse turbines.

50 The universal practice of the art to employ such high velocities in impulse turbines has been based upon a misconception of the efficiency losses of steam flowing over impulse wheels. Well known nozzle experiments by Josse and Christlein (see for example their U. S. Patent No. 1,062,471) had been accepted as proving that in all impulse turbines the maximum efficiency was obtainable when the steam velocity at each stage considerably exceeds the critical velocity of about 450 meters per second from 10% to 60%. While these values have been departed from in the construction of impulse turbines, the velocities employed have always been of this order of magnitude. In the 55 first or highest pressure stage of back pressure turbines the greatest heat drop occurred at the first stage and the highest velocity, because variations from the supposed most efficient velocity in either direction, would decrease efficiency, and, therefore, it was preferable to increase the pressure and heat drop, and, therefore, the velocity rather than to decrease it in order to lessen the pressure that the glands must withstand and the temperature upon the turbine parts.

55 My own experiments conducted under conditions that take into consideration the practical conditions of the flow of steam over the blades and through the other parts

of a turbine have developed the fact that there is a quite different and a much lower zone of steam velocities at which a substantially greater efficiency can be obtained than in the zone heretofore supposed to be the best. This zone is that which is ordinarily referred to by engineers in my own country as Rohreibungszone, which translated literally means pipe friction zone, and as technically used means a velocity which gives rise to frictional losses of the order of magnitude of those acceptable in pipe lines, such pipe friction zone velocities in a turbine with its very smooth passages being understood to be higher than ordinarily accepted in pipes with their rough surfaces, but in a completely different zone from that of the velocities of ordinary impulse turbines. In order to give precise information to enable turbines to be best constructed in accordance with my invention, I would say that I ascertained by my experiments that the maximum efficiency is obtainable when the steam velocities relative to the blade surfaces is about 100 meters per second, this efficiency falling off as the relative velocity is reduced from about this figure and as it is increased. The efficiency begins to decrease very sharply at a relative velocity of about 140 meters per second. At a considerably higher velocity the efficiency again begins to increase, in accordance with the rule laid down by Josse and Christlein, but never reaches the high efficiency that I make use of in the lower or pipe friction zone.

As there is in practically all impulse turbines a small reaction effect, the relative velocity cannot be the same at all parts of the blade surface, and therefore, to take the fullest advantage of my invention, the relative velocity at no part of the blade surface should be higher than 140 meters per second. This necessarily means in any practical construction that the absolute velocity of the steam entering each stage of the turbine will also be of a different and lower order of magnitude than any velocities heretofore employed in impulse turbines.

In the drawings accompanying this specification Fig. 1 is a cross-section through one-half of a back pressure turbine embodying the principle of my invention. Fig. 2 on the same scale as Fig. 1 illustrates a similar section of that part of a prior art turbine of the same type designed to utilize the same pressure and temperature drop as would be utilized by the entire turbine of Fig. 1.

Fig. 3 is a diagram illustrating the comparative pressure drops in the turbine of Fig. 1 and the first stage of the turbine of Fig. 2.

Fig. 4 is a diagram illustrating the comparison of the absolute and relative velocities of the turbine of Fig. 1 and the first stage of the turbine of Fig. 2.

My invention consists essentially in the application to back pressure impulse turbines including particularly the first stage thereof of the discovery I have made that the relative steam velocities in turbines reach their highest efficiency in a low velocity zone far below the high zone heretofore thought to be the most efficient. A back pressure turbine constructed in accordance with my invention and utilizing the method thereof has, therefore, only such small heat and pressure drop from the inlet to the highest stage and from each stage to the next as will cause a substantially uniform low pipe friction zone velocity throughout, preferably a relative velocity at all parts of the blades not exceeding 140 meters per second. While this both as a matter of method and as a matter of structure, is, as above pointed out, a reversal of present engineering principles, yet a turbine built in accordance with my invention and adapted to utilize my method differs from the present existing impulse turbines of the disk type in no essential feature except those that are dimensional or matters of degree, and, therefore, the drawings illustrating the embodiments of my invention do so by comparing my turbines with the nearest known prior turbine.

Fig. 1 illustrates a turbine adapted for an inlet pressure of 300 lbs., the exit pressure of this turbine being 140 lbs. The turbine is preferably not constructed for a lower exit pressure, although it could be, because it is preferable to utilize this high pressure in a second similarly designed turbine rather than to utilize the lower pressure in a longer turbine. 1 represents the shaft of the rotor and 2 the casing of the turbine; 3 is the inlet nozzle and 4 the guide passages in the diaphragms 5 supported from the rotor casing; 6 represents the rotor wheels carried by the shaft and 7 the passages through the blading carried by the wheel.

In Fig. 2 is shown that part of a standard prior impulse turbine of the pressure compounded type, the type that I employ which would utilize the pressure drop from 300 lbs. to 140 lbs., the rotor shaft being designated as 1^a, the casing as 2^a, the inlet nozzle as 3^a, a rotor wheel as 6^a, a diaphragm as 5^a and the passage therethrough as 4^a. Additional rotor wheels and diaphragms are not shown in this figure because in such a prior turbine the entire pressure drop from 300 lbs. to 140 lbs. corresponding to the pressure drop in the multi-stage back pressure turbine of Fig. 1 occurs at the first stage. Most existing impulse turbines for such large inlet pressure have a considerably greater pressure drop in the first stage than at the one just specified.

Figs. 1 and 2 are drawn to the same di-

dimensional scale in order that the difference in principle and the resulting difference in details of construction may be best observed. Because the low, or pipe friction zone, velocity is employed throughout my turbine as the relative velocity thereof, the numerous stages shown in Fig. 1 are used instead of the single stage of Fig. 2 to utilize the power of the steam for the pressure drop between 300 and 140 lbs., thus making a much longer high pressure part of the turbine. For the same reason the peripheral velocity of the rotor is necessarily very much less and therefore the diameter of the rotor or height of rotor blading can be much reduced. The difference in this respect is illustrated in Figs. 1 and 2. For the same reason the shaft diameter may be much reduced, wherefore the gland diameter is likewise reduced and the glands are capable of withstanding the higher pressure. As the entire pressure drop of the turbine of Fig. 1 is found in the first stage of the turbine of Fig. 2, it is obvious that the inlet nozzle as shown in Fig. 2 is as large as the exit nozzle of the turbine of Fig. 1 and that the inlet nozzle of Fig. 1 is very much smaller while the passages through the various diaphragms of Fig. 1 progressively increase but are all smaller than the inlet of the turbine of Fig. 2. As there is in Fig. 2 a pressure on opposite sides of the diaphragm 5^a equal to the sum of the differences of pressures on the opposite sides of the numerous diaphragms of Fig. 1, the diaphragms of Fig. 1 can all be made lighter and thinner than those of Fig. 2, as indicated in these figures. The fundamental difference between the new turbine of Fig. 1 and the nearest existing turbine the first stage of which is shown in Fig. 2 is further shown by comparing the Figs. 3 and 4. In Fig. 3 the line 8 shows the pressure changes from 300 pounds to 140 pounds in the turbine of Fig. 1. The line 9 shows the same drop in the single first stage of the turbine of Fig. 2. Similarly in Fig. 4 the comparative velocities are illustrated. The lines 10 show the velocities developed in the guide blades or guide nozzles of the turbine of Fig. 1, while the horizontal lines 10^a show the substantially relative uniform velocities in the rotating blades. Similarly, the line 11 illustrates the high velocity through the inlet nozzle of the turbine of Fig. 2, while the line 11^a shows the relative velocity in the rotor blades of the first stage. It is to be understood that in the turbines taking the full use of the well known Josse and Christlein principle, higher velocities than those shown in Figure 4 would appear, and the pressure drop would be greater than shown in Fig. 3.

The general design of Fig. 1 can as well be used for very much higher pressures, the

number of stages varying according to the total pressure and heat drop for which the back pressure turbine is desired, but whatever the inlet pressure, the low zone relative velocity is substantially uniform throughout the turbine.

Having thus described my invention, what I claim, and desire to protect by Letters Patent, is:

1. A back pressure steam turbine of the impulse type having sufficiently many stages and guide passages proportioned throughout to cause a substantially uniform relative velocity of the steam at all stages, including the highest stage, such velocity being in the low velocity zone where the losses are those corresponding to pipe friction losses as contradistinguished from the high velocity zone heretofore recognized as the turbine efficiency zone. 75
2. A back pressure steam turbine having many pressure stages and impulse wheels therein and provided with an inlet to its highest stage so small that the pressure and temperature therein are nearly those of the steam applied to the inlet, thus causing a velocity so low as to increase the efficiency above those of like turbines employing known velocities of over 450 meters per second. 80
3. A high pressure turbine having back pressure and provided with many stages with an impulse wheel for each, the inlet and guide passages each giving sufficiently small drops of pressure that a low zone of steam velocity where efficiency is high is found in every stage in contradistinction to the recognized high velocity efficiency zone for turbines. 85
4. A high pressure steam turbine having a back pressure provided with many stages and impulse wheels therein, the inlet passages and the guide passages each giving sufficiently small drops of pressure that a low zone steam velocity where efficiency is high is found in every stage in contradistinction to the known efficiency zone above 450 meters per second. 100
5. The method of utilizing high pressure steam for power purposes in turbines of the impulse type which consists in reducing the pressure and temperature drop of such steam by a plurality of drops each such as to produce a substantially uniform relative velocity in a low zone of steam velocity where efficiency is high as contradistinguished from the known high velocity efficiency zone. 115
6. The method of utilizing high pressure steam for power purposes in turbines of the impulse type which consists in reducing the pressure and temperature drop of such steam by a plurality of drops each such as to produce a substantially uniform relative velocity in a low zone of steam velocity where efficiency is high as contradistinguished from 125

the known high velocity efficiency zone, the steam after passing through all said stages still having a high pressure and temperature.

- 5 7. The method of utilizing high pressure steam in back-pressure impulse turbines which consists in first reducing the pressure and temperature of the steam in such small degree as to produce a dense stream of a
10 velocity in a low zone where its thermodynamic efficiency is relatively high as contradistinguished from velocities in or above the known high velocity efficiency zone causing this low velocity stream to act upon the

blading of an impulse wheel of a turbine, 15 then reducing the pressure and temperature by similar small but progressively increasing drops such that said low zone velocity shall be maintained at each stage, and causing the steam after each such drop to act 20 upon another impulse wheel of the turbine, whereby back-pressure impulse turbines may be designed of increased efficiency as contrasted with any efficiency obtainable in the high velocity zone of over 450 meters. 25

In testimony whereof I have signed my name to this specification.

FRANZ LÖSEL.
